UNITED STATES PATENT OFFICE.

JOHN W. HYATT, OF NEWARK, NEW JERSEY.

SHOE FOR PNEUMATIC TIRES.

No. 814,377.

Specification of Letters Patent.

Patented March 6, 1906.

Application filed May 22, 1905. Serial No. 261,582.

To all whom it may concern:

Be it known that I, JOHN W. HYATT, a citizen of the United States, and a resident of 141 Commerce street, Newark, county of Essex, and State of New Jersey, have invented 5 certain new and useful Improvements in Shoes for Pneumatic Tires, fully described and represented in the following specification and the accompanying drawings, forming a 10 part of the same.

The object of the present invention is to furnish an improved construction for an endless trough-shaped shoe for pneumatic tires, one adapted to thoroughly sustain the expansive pressure of the pneumatic tube, to 15 yield in a suitable degree to the pressure of the load, and one in which the principal strain may be sustained by strands or threads 20 extended directly from edge to edge of the fabric which forms the shoe.

The invention is especially adapted for the manufacture of shoes having wire rings at opposite edges to confine them in the wheel- 25 rim; but the article covers, broadly, an endless trough-shaped shoe comprising a spirally-wound warp with a transverse filling, having selvages at the opposite edges of the shoe. Such a shoe is made trough shape in cross-section with the opening of the trough to- 30 ward the center of the shoe, and wire rings applied to the edges of the trough are therefore smaller in diameter than any other part.

In the manufacture of this article I form the warp by winding a cord or a series of parallel cords spirally (over a suitable former) 35 into circular trough shape, the winding commencing at one of the edges of the shoe and the cord or series of cords being wound once around the former and the end or ends fastened to the adjacent coil, the winding of the cord being then continued into progressively larger spirals until the center of the shoe is reached, which forms the outermost diameter of the same, and the winding then forming 45 decreasing spirals to the opposite edge of the tire, where the end of the cord is attached to the last winding-coil. To sew or weave a filling transversely upon such a warp, I flatten the same upon a transverse line at one part 50 of the periphery, which permits the application of sewing or weaving instrumentalities to connect the cords of the warp together transversely and form a selvage at both edges of the fabric. By supporting wire rings ad- 55 jacent to the edges of the trough the transverse filling can be made to embrace and

wholly cover such wire rings and unite them securely to the cords of the warp.

The invention will be understood by reference to the annexed drawings, in which—

Figure 1 is a side elevation of a diagrammatic character, showing the warp for one of the shoes with a part of the filling applied transversely to the warp and illustrating some of the agencies for sewing the same. 65 Fig. 2 is a plan of the same with the warp-strands formed from a single spirally-wound cord and the opposite sides of the shoe being indicated merely by dotted lines. Fig. 3 shows the strands of the warp formed of a fine 70 cord with its coils divided into groups. Fig. 4 is a cross-section on line 4 4 in Fig. 1. Fig. 5 is an elevation of the comb shown in Fig. 4. Fig. 6 is a cross-section on line 6 6 in Fig. 7, and Fig. 7 shows in diagrammatic form a 75 warp wound from a large cord with endless wire rings at its opposite edges. Figs. 1 to 7 are drawn upon a very small scale, while the remaining figures are drawn upon a much larger scale, Fig. 8 showing one edge of the 80 fabric formed by stitching the warp-threads together transversely and Fig. 9 the opposite edge where the selvage is differently formed. Fig. 10 shows a piece of cord adapted to form a complete strand of the fabric. Fig. 11 is a 85 cross-section of the shoe with the longitudinal strands and the transverse stitching-loops shown upon a part of the same to illustrate their formation and their connection with the wire ring at the edge of the shoe.

To illustrate a spiral winding of the warp, a coarse cord is shown in Fig. 7 wound into fourteen coils a a' a'' , suitable for separate strands, and the opposite ends of the cord connected to the last coil by the wrappings b . 95 Endless wire rings c are shown at opposite edges of the coils, the section in Fig. 6 showing the trough-shaped disposition of the coils and rings, which makes the coils a at the edges the smallest in diameter and the coil a'' at the 100 center of the width the largest in diameter, while the intermediate coils a' are of intermediate diameter. To connect such coils by a transverse filling, the coils and rings c are supported in a suitable manner and the trough 105 flattened transversely for a small space d , as shown in Fig. 1, so that it may be supported by a bed e and the filling connected with the warp-strands. A row of comb-teeth f is shown extended transversely across 110 the bed to separate the strands of the warp, and one of a row or gang of sixteen needles g

is shown in Fig. 1 carrying a filling-thread *h*. The needle-bar *i*, carrying the row of needles, is in practice reciprocated so as to carry each of the filling-threads transversely across one of the strands, as shown at *h* in Fig. 11, an under thread *l* being inserted by suitable means through the loops of the several threads *h* and connected to the same at the edges of the fabric to form a selvage, as shown, where the wires *j* are illustrated in Figs. 8 and 9. The warp would be fed in the direction of the arrow *m* in Fig. 1, and the transverse filling is shown completed from the needles *g* to a point *g'* upon the warp. The wire ring in such tires is commonly formed of several coils of piano-wire with the ends soldered together, thus forming a rigid inextensible ring, and several of such wires *j* are shown forming the ring in Figs. 8, 9, and 11. An opening *k* is shown in the bed *e* for the passage of the row of needles *g*; but it is immaterial what means be used for applying the transverse filling to the warp-strands, as weaving or sewing devices of any suitable character are equivalent to one another for such purpose.

In connecting the warp-strands by a transverse filling the coils of the warp are divided by the transverse comb adjacent to the point where the filling is applied into strands which may consist each of a single large cord, such as is shown in Fig. 10, or of a group of smaller cords, as shown in Fig. 3. Where the warp is made with a large cord, it is wound with the same number of coils as the spaces in the comb, as shown in Figs. 2, 5, 6, and 7, each cord forming a strand of the warp, (lettered *a*³ in Fig. 2,) and the filling is applied in such manner as to lay transverse threads above and below such strands and to connect such threads between the several strands. Where the warp is made from a small cord, the comb operates to separate the coils into groups forming strands *a*⁴, as shown in Fig. 3, which groups are connected transversely in the same manner as the larger cords. (Shown in Fig. 2.) The strands connected transversely by the filling-threads *h* and *l* in Figs. 8 and 9 would operate precisely the same whether formed of a single large cord or of a group of small cords, as shown, respectively, in Figs. 2 and 3.

Such shoes are in practice coated with india-rubber to protect them from moisture and wear, and such rubber is molded thereon under pressure and then vulcanized, and such coating of india-rubber is indicated at *n* upon the left side of Fig. 11, where seven of the strands are fully shown. It will be observed in this figure that the under thread *l* extends transversely across the inner side of the shoe and serves by its connection at the selvage with the wire rings to firmly resist the expansion of the pneumatic tube when secured over the same. The outer looped threads *h*

do not extend directly across the strands and do not therefore, resist such expansion; but their looped connection with the under thread *l* gives the fabric a great degree of flexibility and permits it to yield under the load much more readily than if threads extended straight across the inner and outer sides of the fabric. The extension of the outer thread to the inner side of the fabric in the form of loops also forms channels or grooves *p* between the strands into which the rubber coating can be forced when molded upon the fabric, and the tongues of rubber extending into such grooves form a strong and elastic junction between the coating and the fabric, and thus secure the adhesion of the rubber, while permitting the fabric to yield in the desired manner.

The durability of the tire is increased if the strain of the pneumatic tire is sustained chiefly by the threads extending directly across the shoe from one of the wire rings to the other and if less of the strain be sustained by or transmitted to the strands of the warp.

It is found in practice very difficult to hold the strands slack during the application of the filling to the strands, so as to secure any slackness of the spiral coils when the fabric is finished; but such slackness can be positively secured by moistening the cord before it is wound into the form of a warp, which has the effect of shortening the cord. By applying the transverse filling to the warp while the warp is in this moistened condition the fabric can be completed, and when afterward dried the coils of the warp become slightly lengthened, which produces a slight amount of slackness and relieves them from any excessive tension to strain and rupture them.

It is well known that cords and yarns formed of twisted fibers are always shortened by moistening, as such moisture increases the diameter of the cord, and therefore the circuit around it in which the twisted fibers are disposed. The circuit being greater, the fibers are drawn up and the length of the cord is diminished. The moistening of the cord before winding it into the form required for the warp and the maintaining of such a moistened condition during the application of the filling permits the slackening of the warp after the fabric is completed, with the result of throwing the principal strain upon the transverse filling, which extends directly across the shoe.

Where the shoe is provided in the edges with rigid wire rings and the shoe is strained by a pneumatic tube, the loosening of the warp when dried places it under less tension than the wire rings, and thus throws the strain largely upon the rings, which are not at all exposed to wear or flexure in the operation of the tire and are therefore affected less injuriously by such strain.

It will be observed that when the warp is wound spirally a single cord suffices to form

a large number of strands, which by sewing or weaving operations may be supplied with a suitable transverse filling, and Figs. 2 and 3 show that such strands may be formed of 5 a continuous spirally-wound cord whether such cord be made of the same size as a single strand, as in Fig. 2, or very much smaller, as in Fig. 3. The spiral arrangement of the strands permits all the strands to be formed of a single cord, and it is obvious that strands can be wound upon a suitable former with much greater facility when disposed spirally than if endless circular strands were employed, which require to be wound separate from one another. It is obvious that the advantages of the invention in this respect would be secured if two spiral cords were employed and each extended from one edge of the shoe to the middle or largest coil. Such 15 a construction would be a mere evasion of my invention, as it would obviously be an equivalent, and this will be fully understood from the fact that in practice thirty or forty strands are required to make a trough-shaped 20 shoe which is at least eight inches wide when flattened for sewing, and where it is desired to form the strands of a fine cord about two hundred coils of the cord would be required to produce the forty strands of five cords 25 each. Such division of the cords into strands may be effected after the winding by means of the comb shown in the drawings, where only fourteen of the strands are shown in order that the construction may be more clearly 30 represented.

In practice the forward feed of the warp as the filling is applied thereto is in a spiral direction, following the inclination of the strands which is shown in Figs. 4 and 7, and 35 when the feeding movement brings the wrappings *b* (shown in Fig. 7) against the comb such wrappings are cut and removed, so as to permit a complete rotation of the warp beneath the filling appliances, the filling 40 already applied then serving to hold the strands in place instead of the wrappings.

The advantages of the present invention lie in the formation of a fabric with rings at the edges which are engaged in a selvage 45 upon the filling of a circular warp and in the formation of the warp by means of a spirally-disposed cord, which greatly facilitates the winding of the warp into a suitable trough-like shape.

Having thus set forth the nature of the invention, what is claimed herein is—

1. An endless trough-shaped shoe for pneumatic tires, comprising an endless warp with wire rings at opposite edges and a transverse

filling having selvage at opposite edges, engaging such rings. 60

2. An endless trough-shaped shoe for pneumatic tires, comprising a spirally-wound warp with a transverse filling having selvages at the opposite edges of the shoe. 65

3. An endless trough-shaped shoe for pneumatic tires, comprising a continuous spirally-wound warp with a transverse filling of sewed stitches forming a selvage at the opposite edges of the shoe. 70

4. An endless trough-shaped shoe for pneumatic tires, comprising a spirally-wound warp with wire rings at opposite edges, with a transverse filling having selvages embracing the wire rings. 75

5. An endless trough-shaped shoe for pneumatic tires, comprising a spirally-wound warp with wire rings at opposite edges, and a transverse filling of sewed stitches forming a selvage at the opposite edges embracing the wire rings. 80

6. An endless trough-shaped shoe for pneumatic tires, having a single continuous spiral cord comprising the warp, and a filling of transverse stitches dividing the coils of the cord into groups, whereby the lateral flexibility of the shoe is secured. 85

7. An endless trough-shaped shoe for pneumatic tires, having a single continuous spiral cord comprising the warp, and a filling of transverse stitches dividing the coils of the cord into groups with intermediate channels between the groups upon the outer side of the shoe, to admit the india-rubber coating between the groups. 90

8. An endless trough-shaped shoe for pneumatic tires, having a single continuous spiral cord comprising the warp, with wire rings at opposite edges, and a filling of transverse stitches dividing the coils of the cord into groups, with a selvage at each edge of the shoe embracing the said wire rings. 95

9. A trough-shaped shoe for pneumatic tires comprising a spirally-wound warp, a filling of transverse stitches forming continuous parallel strands with continuous channels or grooves *p* between the same, and an india-rubber coating forced into such grooves, the grooves and rubber tongues in the same permitting great flexibility in the fabric. 100

In testimony whereof I have hereunto set my hand in the presence of two subscribing witnesses.
